(57) **CLAIM**

The ornamental design for a housing for communications devices or similar articles, as shown.

DESCRIPTION

FIG. 1 is a perspective view of an ornamental design for a housing for a communication device or similar articles.

FIG. 2 is a first side elevation view of FIG. 1.

FIG. 3 is a front elevation view of FIG. 1.

FIG. 4 is a bottom plan view of FIG. 1.

FIG. 5 is a top plan view of FIG. 1.

FIG. 6 is a second side elevation view of FIG. 1; and,
FIG. 7 is a rear elevation view of FIG. 1.

The broken line portions of the drawings are not part of the claimed design.
